PIPE CUTTING TOOL

John D. Brack, Sulphur, and Lantrop M. York,
Lake Charles, La.Application June 7, 1938, Serial No. 212,364
Renewed March 2, 1940

13 Claims. (Cl. 164—0.4)

This invention relates to a pipe cutting tool and particularly pertains to a tool especially designed for use in cutting pipes in wells and the like.

5 It is an object of the invention to provide a tool of this kind which can be employed to cut the pipe at any desired depth.

It is also an object of the invention to provide a tool of this character so constructed and assembled whereby the cutters are caused to extend as a result of a rotative action and retracted as a result of fluid pressure.

10 The invention consists in the details of construction and in the combination and arrangement of the several parts of our improved pipe cutting tool whereby certain important advantages are attained and the device rendered simpler, less expensive and otherwise more convenient and advantageous for use, as will be 15 hereinafter more fully set forth.

The novel features of our invention will hereinafter be definitely claimed.

20 In order that our invention may be the better understood, we will now proceed to describe the same with reference to the accompanying drawings, wherein:

25 Figure 1 is a longitudinal sectional view taken through the upper portion of the tool as herein comprised, certain of the parts being in elevation;

30 Figure 1^a is a view similar to Figure 1 taken through the lower portion of the tool as herein disclosed, the ends A—B in the complete tool being in continuation;

35 Figure 2 is a fragmentary longitudinal sectional view taken through the central portion of the tool as herein disclosed with the cutters fully extended;

40 Figure 3 is a sectional view taken substantially on the line 3—3 of Figure 1;

Figure 4 is a sectional view taken substantially on the line 4—4 of Figure 1;

45 Figure 5 is a sectional view taken substantially on the line 5—5 of Figure 1^a;

Figure 6 is a sectional view taken substantially on the line 6—6 of Figure 1^a.

50 As disclosed in the accompanying drawings, 1 denotes a tubular coupler for connection in a conventional way with a tubular string or pipe line (not shown) but which, as is well known, extends above the ground surface and has operatively engaged therewith suitable mechanism whereby the same may be rotated.

55 Threading, as at 2, within the lower portion of the coupler 1 is an elongated tubular tool body 3 of desired dimensions and threading, as at 4,

into the lower end portion of this body 3 is a block 5. This block 5 has depending from its central portion an elongated cylindrical tubular member 6, the bore 7 of which is open at both ends and extended up through the block 5. Freely surrounding the member 6 is a sleeve 8, the same being maintained in applied position by a holding nut 9 threading upon the free extremity of the member 6 below the sleeve 8. The wall of the sleeve 8 is relatively thick and is provided in its periphery at equidistantly spaced points there-around with the longitudinally disposed recesses 10 having their upper end portions undercut, as at 11. Freely or loosely extending within these slots or recesses 10 are the elongated holding cleats or friction dogs 12 which are constantly urged outwardly by the springs 14 interposed between the cleats or dogs 12 and the bottoms of the slots or recesses 10. The upper ends of the cleats or dogs 12 are provided with the outstanding lugs 15 which extend within the undercut portions 11 while the lower or opposite end portions of the cleats or dogs 12 are provided with the outstanding lugs 16 which extend within the open end portion of a cap member 17 which threads upon the lower portion of the sleeve 8. The lower portion of this sleeve 8 is preferably slightly reduced so that the periphery of the applied cap 17 will be substantially flush with the periphery of the sleeve 8. These lugs 15 and 16 provide means whereby the outward movement of the cleats or dogs 12 is limited. The cleats or dogs 12 are to have frictional contact from within in a well pipe or casing whereby the lowered tool is effectively maintained at desired depth within the pipe or casing yet permitting desired rotation of the body 3 during a cutting operation.

Extending upwardly through the bore 7 of the member 6 and the block 5 and for a desired distance upwardly within the body 3 is the elongated rod 18 the lower end portion of which is threaded, as at 19, or otherwise fixedly secured to the central portion of the cap 17.

The body 3 is provided at points intermediate its ends with the opposed elongated slots 20 in 45 which are disposed the rock levers 21 which constitute holders for the cutters or bits 22 which are engaged within recesses 23 provided in the lower end portions of the levers 21. The levers 21 are mounted for swinging or rocking movement on the pins or shafts 24 which extend across the slots 20 with the extremities of said pins or shafts received within the suitably located openings 25 provided in the wall of the body 3 at opposite sides of the slots 20. These slots 20 are positioned a 50

material distance below the upper end of the rod 18.

Freely surrounding the rod 18 for movement lengthwise thereof in either direction is an elongated driving mandrel M. The lower end portion of this mandrel M is formed to provide an elongated and substantially cone-shaped operating member 26, the apex portion of which is upwardly disposed. The upper end portion of this mandrel 10 M is formed to provide a second operating member 27 having its inner portion 28 substantially cone-shaped with its apex downwardly disposed. The tapered wall of the portion 28 of the member 27, as herein disclosed, is on a greater angle than 15 the periphery of the member 26 and said portion 28 of the upper operating member 27 is of a length materially less than the length of the lower operating member 26.

Upon upward movement of the mandrel M the 20 operating member 26 will pass between and contact with the lower end portions of the dogs 12 and force the same together with the cutters or bits 22 outwardly to assure the desired cutting of a casing or pipe as the body 3 is rotated. 25 Upon downward movement of the mandrel M the operating member 27, or more particularly the portion 28 thereof, will engage the upper beveled portions 29 of the levers 21 and thereby swing the lower end portions of said levers 21 together 30 with the cutters or bits 22 inwardly of the body 3.

The intermediate portion 30 of the mandrel M is of such diameter and length to assure the desired endwise movement of the mandrel M with 35 respect to the levers 21. Interposed between the lower end of the mandrel M and the applied block 5 is a stabilizing spring 31 of desired tension and which, as particularly illustrated in Figure 1^a, is of a coil type surrounding the rod 18.

Snugly engaged within the body 3 above the 40 mandrel M is a piston P having its lower end continued by an elongated skirt or sleeve 32, and the piston P proper is provided with a surrounding depression or packing ring 33 to assure effective coaction between the piston P and the body 3. 45 The lower end of this piston P is provided with a recess or socket 34 to receive the upper end portion of the rod 18 so that said rod 18 will offer no hindrance or obstruction to the desired downward movement of the piston P.

50 Threading into, as at 35, or otherwise effectively coupled to the lower portion of the sleeve or skirt 32 of the piston P is the upper end portion of a short sleeve or bowl member 36, the upper portion 37 of the bore of which is outwardly flared or tapered. This sleeve or bowl member 36 is provided with the radially extending and 55 oppositely directed pins or keys 38 which extend within the longitudinally disposed slots or keyways 39 provided in the wall of the body 3 in the upper portion thereof. It will, therefore, be noted that the sleeve or bowl member 36 readily moves with the piston P but is held against rotation independently of the body 3.

Within the tapered portion 37 of the bore of the 60 sleeve or bowl member 36 and at opposite sides of the rod 18 are the nut sections 40, the outer or back faces of which are tapered or flared complementary to the tapered or flared portion 37 of the sleeve or bowl member 36 so that as a result of upward movement of the piston P the 65 nut sections 40 will be adjusted into and maintained in proper engagement with the threaded portion 41 at the upper portion of the rod 18. This upward movement of the piston P is obtained by the expansible member 42 of requisite

tension and which is herein disclosed as a coil spring encircling the upper portion of the rod 18 and interposed between the inner end of the piston P and the upper ends of the nut sections 40.

5 As the piston P is moved downwardly the resultant downward movement of the sleeve or bowl member 36 will readily allow the nut sections 40 to freely pass down along the threaded portion 41.

10 As is herein disclosed the nut sections 40 are carried by the upper extremities of the rigid arms 43 of desired length and which extend down through and below the sleeve or bowl member 36 and are pivotally connected, as at 44, within the 15 radially disposed groove or channel 45 of desired width and depth extending across the upper or top face of the upper operating member 27.

20 When the nut sections 40 are in operative engagement with the threaded portion 41 of the rod 18 and as the body member 3 is rotated to the right, the mandrel M will be caused to travel upwardly on the member 18 and thereby effect the desired outward movement of the cutters or bits 22. It is to be stated that the spring 42 25 is of sufficient tension to resist this upward movement of the mandrel M so that the piston P will have corresponding movement. The cleats or friction dogs 12 have sufficient contact with the well casing or well wall to hold the same against 30 rotation as the member 3 is rotated whereby is assured the proper functioning of the tool. While not illustrated, it is to be stated that when desired the outer faces of the dogs or cleats 12 may be provided with the conventional biting shoulders 35 to further assure the desired holding function of the dogs or cleats.

25 After the completion of the cutting operation mud or other liquid pumped down upon the piston P will provide sufficient pressure to move the 40 piston P downwardly sufficient to allow release of the nut sections and after the bowl member or sleeve 36 engages the upper end of the mandrel M said mandrel will be moved downwardly to cause the upper operating member 27 to engage 45 the levers 21 and retract the cutters or bits 22 within the body 3 as illustrated in Figure 1^a. The tool can then be readily withdrawn or adjusted to a second position for a further cutting operation.

50 From the foregoing description it is thought to be obvious that a pipe cutting tool constructed in accordance with our invention is particularly well adapted for use by reason of the convenience and facility with which it may be assembled and 55 operated, and it will also be obvious that our invention is susceptible of some change and modification without departing from the principles and spirit thereof and for this reason we do not wish to be understood as limiting ourselves to 60 the precise arrangement and formation of the several parts herein shown in carrying out our invention in practice except as hereinafter claimed.

65 We claim:

1. An inside cutting tool comprising a body, laterally movable cutting means carried by the body, a pair of longitudinally movable reversely tapered operating members carried by the body and selectively engaging with the cutting means 70 for moving the cutting means relative to the body, said operating members being constructed and arranged to move in unison and in the same direction, means for moving the operating members in one direction whereby one of the operat- 75

- sure operated means for moving said cutting means to inoperative position, and means active upon movement of said fluid pressure operated means to disengage said threaded operating means.
- 5 10. A cutting tool as set forth comprising an elongated body, a pair of cutting members, means for movably mounting said cutting members in said body, operating means for said cutting members carried by the body, threaded means engageable with said operating means and active on rotation of the body to effect outward movement of the cutting members, and fluid pressure operated means independent of the rotation of the body to move said cutting members to inoperative position.
- 10 15. A cutting tool as set forth comprising an elongated body provided with openings, cutting members disposed in said openings and movable laterally of the body, an operating member for said cutting members disposed interiorly of the body and movable longitudinally thereof, means for moving said operating member longitudinally of the body upon rotation thereof, said latter 20 means including a pair of threaded members, one of said threaded members being movable longitudinally with said operating member, means engageable with the interior of the pipe to hold the other of said threaded members against rotation to thereby effect longitudinal movement of the operating member upon rotation of the body, and means for disengaging said other threaded member.
- 25 30. 12. A cutting tool as set forth comprising an elongated hollow member provided with opposed openings in a wall thereof intermediate the ends thereof, levers, means for rockably mounting said levers in said openings, a cutter secured to each lever adjacent an end thereof, an operating member disposed within the body and movable longitudinally thereof, a releasing member connected to said operating member and movable therewith, means active upon rotation of the body to move said operating member in one direction to thereby swing said cutters laterally of the body into operative position, and means disposed within the body to release the operating member, said latter means including means to effect movement of the releasing member to effect retraction of the cutters into the openings of the body.
- 10 15. 13. A cutting tool comprising an elongated hollow body, a pair of cutting members carried by the body and movable laterally thereof to operative position, means movable longitudinally of the body in one direction to move said cutting members to operative position, means movable longitudinally of the body in the opposite direction 20 to move said cutting members to release position, threaded means for moving said first named means in said one direction, and fluid pressure means for moving said second named means in the opposite direction.
- 25 30. JOHN D. BRACK,
LANTROP M. YORK.
